UNITED STATES PATENT OFFICE.

LOTHIAR VON GRAVE, OF WALLINGFORD, CONNECTICUT, ASSIGNOR TO THE
II. L. JUDD & COMPANY, OF NEW YORK, N. Y.

DESIGN FOR A PICTURE-FRAME, &c.

SPECIFICATION forming part of Design No. 23,386, dated June 19, 1894.

Application filed May 10, 1894. Serial No. 510,802. Term of patent 3½ years.

To all whom it may concern:

Be it known that I, LOTHIAR VON GRAVE, a subject of the Emperor of Germany, residing at Wallingford, New Haven county, State of Connecticut, have invented and produced a new and original Design for Frames for Pictures, Mirrors, and the Like, of which the following is a specification, reference being had to the accompanying drawing, which shows a face view of a frame illustrating my design.

The essential features of my design consist of stem-like projections extending in from the ornamental body proper of the frame, and ornamental scroll-like projections extend out from said body proper for a considerable distance, some of which outwardly extending portions constitute feet for the frame.

In the drawing, *a* represents the ornamental body proper of the frame from which extend inward ornamental stem-like projections *b*. Extending outward from the body portion of the frame are ornamental projections *c*, some of which constitute the feet for the frame. 20

What I claim is—

The design for frames for pictures, mirrors and the like, substantially as shown and described. 25

LOTHIAR VON GRAVE.
